O. B. WHISENAND.

ADJUSTING DEVICE FOR THROTTLE GOVERNORS.

APPLICATION FILED NOV. 26, 1919.

1,424,270.

Patented Aug. 1, 1922.

UNITED STATES PATENT OFFICE.

OMER B. WHISENAND, OF INDIANAPOLIS, INDIANA, ASSIGNOR TO SWARTZ ELECTRIC COMPANY, OF INDIANAPOLIS, INDIANA, A CORPORATION OF INDIANA.

ADJUSTING DEVICE FOR THROTTLE GOVERNORS.

1,424,270.

Specification of Letters Patent. Patented Aug. 1, 1922.

Application filed November 26, 1919. Serial No. 340,931.

To all whom it may concern:

Be it known that I, OMER B. WHISENAND, a citizen of the United States, residing at Indianapolis, in the county of Marion and State of Indiana, have invented certain new and useful Improvements in Adjusting Devices for Throttle Governors, of which the following is a specification.

This invention relates to an adjusting device for throttle governors, and is especially adapted for throttle governors wherein an operating plunger is acted upon by fluctuations in the current passing through a solenoid, and it is among the objects of this invention to devise a governor of this type which can be readily adjusted to vary at will the voltage generated by the system.

Throttle governors of the type to which this invention is applicable are so constructed that when the voltage in the generator, which is operated by an engine, reaches a certain point the throttle valve is choked off so that the output of the generator is held at a predetermined voltage. It is often desirable that this voltage be readily changed or adjusted, and my present invention contemplates a simple means for accomplishing this result.

In carrying the objects of my invention into effect, I fix the solenoid to a movable portion of the governor casing and provide means whereby the solenoid may be shifted relatively to the plunger operating within it, and means are provided for clamping the solenoid in any of its adjusted positions to a fixed portion of the governor casing. I may, if it is deemed desirable, calibrate the movable portion of the casing to indicate the voltage to which the governor is adjusted in its various positions.

Referring to the accompanying drawings forming a part hereof and in which similar reference characters denote similar parts,

Figure 1, represents an elevation of a throttle governor with my adjusting device attached, and

Figure 2, a sectional view taken transversely as indicated on the line 2—2 of Figure 1, some parts being shown in elevation.

The casing 1 of the throttle governor is secured in any well known manner to the manifold pipe 2 in which the throttle valve of the engine is located, and has a downwardly extending sleeve 3. Within the

sleeve is a movable casing 4 having fixed 55 within it the solenoid 5, the casing being adapted to slide in the sleeve. Conductor leads 6 from the solenoid are connected to a suitable portion of the dynamo load line. A thumb screw or slotted set screw 7 is fitted 60 into a threaded portion 8 of the sleeve 3 and is adapted to bear against the movable casing 4 which carries the solenoid, and holds it in adjusted positions. Within the solenoid is the plunger 9 attached to the plunger rod 10 which operates the throttle valve and having a spring 11 operatively connected therewith, as shown and described in the co-pending application of Ira T. Swartz, Serial No. 338,751, filed November 17, 1919, 70 on electromagnetic throttle governor. I sometimes place the indicating marks 12 along the movable casing 4 for more easily determining the proper adjustment of the solenoid and its casing to produce a given 75 voltage.

Although I have specifically described my invention including a thumb screw threaded in the stationary portion of the casing, it is to be understood that equivalent devices may 80 be substituted therefor, and that various other changes may be made in the construction, all of which I consider to be within my invention.

Having thus fully described my said invention, what I claim as new and desire to secure by Letters Patent, is:

1. A throttle governor comprising a casing, throttle governing means including a plunger connected to said casing and to the 90 throttle valve of an engine, a second casing slidably mounted in parts of the first casing, a solenoid mounted in the second casing, and means for adjusting said second casing for regulating the position of said solenoid 95 relatively to said plunger.

2. A throttle governor comprising a casing, throttle governing means including a plunger connected to said casing and to the 100 throttle valve of an engine, a solenoid, said plunger operating within said solenoid, said solenoid being fixed to a movable casing, a sleeve formed in said governor casing to allow said movable casing to slide therein, and a screw threaded in said sleeve adapted 105 to clamp said movable casing in any desired position.

3. In a throttle governor a casing, a down-

wardly extending sleeve formed thereon, a movable casing having a solenoid fixed therein within said sleeve, and means for adjusting said movable casing relatively to 5 said sleeve.

4. In a throttle governor a casing, a downwardly extending sleeve formed thereon, a movable casing having a solenoid fixed therein within said sleeve, means for adjusting said movable casing relatively to 10 said sleeve, and indicating means for deter-

mining the proper adjustment of said solenoid.

In witness whereof, I have hereunto set my hand and seal at Indianapolis, Indiana, 15 this 24th day of November, A. D. nineteen hundred and nineteen.

OMER B. WHISENAND. [L.S.]
